UNITED STATES PATENT OFFICE.

DAVID FARQUHAR, OF BUFFALO, NEW YORK, ASSIGNOR TO THE PITTS AGRICULTURAL WORKS, OF NEW YORK.

DESIGN FOR A TOOTH FOR THRESHING-MACHINE CYLINDERS.

SPECIFICATION forming part of Design No. 26,994, dated April 27, 1897.

Application filed December 31, 1896. Serial No. 617,659. Term of patent 14 years.

To all whom it may concern:

Be it known that I, DAVID FARQUHAR, of Buffalo, in the county of Erie and State of New York, have invented a certain new, useful, 5 and original Design for Threshing-Machine-Cylinder Teeth; and I do hereby declare the following to be a full, clear, and exact description of the invention, such as will enable others skilled in the art to which it appertains to 10 make and use the same.

This is a design for teeth for threshing-machine cylinders.

In the accompanying drawings, Figure 1 is a view in perspective. Fig. 2 is a side view. 15 Figs. 3 and 4 are opposite end views. Fig. 5 is a horizontal sectional view on line 5 5, Fig. 3. Fig. 6 is a view of a slight modification. Fig. 7 is a transverse section thereof.

In carrying out my invention I form the 20 body A with tapered slightly-concaved sides 1, extending from enlarged or thickened head 2 and terminating in a reduced end 3. From the head 2 extends a cylindrical portion a, the base a' of which is curved or rounded at a² 25 and flattened at a³. The said curvature terminates at the ends of the flattened side, or the corners may be cut off, as shown in Figs.

6 and 7. The base is tapered throughout its length on both its flattened and curved portions, the widened ends being adjacent to the 30 body A.

The essential features of my design are, first, the body A, having tapered sides 1, cylindrical portion a, and base a'; second, the body A, portion a, and base a', rounded or 35 curved on one side; third, the body A, portion a, and base a', flattened on one side; fourth, the body A, portion a, and base a', tapered; fifth, the body A, portion a, and base a', rounded or curved on one side, flattened 40 on another side, and tapered throughout its length.

I claim as my invention—

The design for a tooth for threshing-machine cylinders, substantially as shown and 45 described.

In testimony whereof I have signed this specification in the presence of two subscribing witnesses.

DAVID FARQUHAR.
